Patented Dec. 13, 1921.

FIG. 1

FIG. 2

FIG. 4

FIG. 3

Bryson D. Horton, Inventor
By his Attorney
Clifford S. Dunn

UNITED STATES PATENT OFFICE.

BRYSON D. HORTON, OF DETROIT, MICHIGAN.

ELECTRICAL SWITCH.

1,400,288.

Specification of Letters Patent. Patented Dec. 13, 1921.

Application filed November 10, 1917. Serial No. 201,220.

To all whom it may concern:

Be it known that I, BRYSON D. HORTON, a citizen of the United States, residing in Detroit, in the county of Wayne and State of Michigan, have invented certain new and useful Improvements in Electrical Switches, of which the following is a description.

This invention relates to electric fuse-holding switches and with regard to certain 10 more specific features thereof to fuse-holding switches of the pivotally movable type.

The invention has for one of its objects to simplify and otherwise improve the means for associating the switch parts and contacts

15 whereby a fuse-holding carrier may be pivotally moved relatively to its base for the purpose of interrupting the continuity of an electric circuit.

Other objects will be in part obvious and 20 in part pointed out hereinafter, and reference should be had to my co-pending application filed November 10, 1917, Serial No. 201,219.

The invention accordingly consists of the 25 various features of construction, combination of elements and arrangements of parts which will be exemplified by the construction hereinafter set forth and the scope of the invention will be indicated in the following claim.

In the drawings, wherein is shown one of various possible embodiments of my invention,

35 Figure 1 is a plan view of a switch embodying the invention.

Fig. 2 is a longitudinal sectional view taken on the line 2—2 of Fig. 1.

Fig. 3 is a sectional view taken on the line 3—3 of Fig. 1; and

40 Fig. 4 is a sectional view taken on the line 4—4 of Fig. 1.

Referring now more particularly to the drawing, there is indicated at 1 a base block of insulating material, upon which are 45 mounted three sets of fixed contacts 2—2' 3—3' and 4—4'. The set 2—2' is disposed intermediate the other two sets and comprises a pair of angle member contacts having up-standing blades or supporting portions 5 50 against which attaching portions 6 of fuse-holding contacts 7 abut. Each of the fuse-holding contacts 7 is provided in addition to the attaching portion mentioned, with side walls 8 bowed inwardly as at 9, and carried 55 out in the form of spaced parallel contact jaws 10.

A bridging element or carrier is indicated at 11, as being of frame construction, comprising four cylindrical posts 15 connected in pairs by metal clamping elements 16, and the pairs being connected by a cross-bar 17. At their outer ends these posts may be further connected by a head 18 carrying the handle 19 for the purpose of operating the bridging element. On either side of the 65 bridging element one of the metal clamping elements 16 is extended in the form of a flat rectangular projection 20 bent back upon itself as at 21 to provide a double thickness of metal.

The structure being similar on opposite sides of the switch, a description of the structure of one side will be sufficient. The 70 fuse-holding contact 7 has its flat attaching portion abutting the supporting or upstanding portion 5 of the angle member contact 2.

The double thickness of metal on the extension of the clamping element 16 is fitted within the side walls 8 of the fuse-holding contact and all three parts are secured to 75

together in good electrical and retaining connection by a pivot screw 25, which passes through the angle member and the attaching portion 6 of the fuse-holding contact 7 and taps into the double thickness 20—21, of the 80 carrier extension. It is intended that these

parts should be held in good electrical communication with each other, while at the same time permitting pivotal movement of the carrier and fuse-receiving contact 85

90 relatively to the contact 2 fixed on the base. In carrying out this idea a spring disk or washer 26 is interposed between the angle member and a head 27 on the pivot screw 25. By means of this washer and the pivot screw 95

95 a suitable degree of friction may be secured.

Screws 30, which secure the clamping elements 16 on the outer or free end of the carrier, are of suitable length to pass through apertures 31 in blade contacts 32, and also 100 through apertures 33 in fuse-holding contacts 34. The latter are of similar shape and construction to the contacts 7 and between the side walls thereof rectangular metal nuts are positioned into which the 105 screws 30 are threaded. It will be obvious, therefore, that the contacts 32 are movable with the carrier through its pivotal range and preferably these contacts are of the double-throw type, so that if the carrier is 110 moved from the position shown in Fig. 2 through an angle of 180 degrees, the con-

tacts 32 will engage with the contacts 4—4' on the base.

In the embodiment shown, the cylindrical posts 15 are composed of bushings of insulating material reinforced by metal rods of small diameter. It will be obvious that the fuse-holding contacts are relatively insulated on either side of the carrier, it being intended to make the sole electrical connection through detachable fuses 40 preferably of the inclosed type comprising a shell 41 of insulating material, metal end caps 42 and flattened terminals 43 projecting beyond said end caps. These terminals are adapted 10 to be inserted between the parallel jaws of the fuse-receiving clips, whereby electrical communication is established between inner and outer clips on the carrier, so that when the bridging element is moved to cause engagement between the contacts 32 thereof and the fixed contacts 3—3' or 4—4', an electrical circuit will be completed between the base contacts. Particular features of the present invention reside in the association 15 of the various parts and contacts to secure pivotal movement of the carrier relatively to the base, and also to provide simple, inexpensive and compact means for attaching the fuse-receiving contacts to the carrier and 20 in turn to the base.

As many changes could be made in the above construction and as many apparently widely different embodiments of the invention could be made without departing from the scope thereof, it is intended that all matter set forth in the foregoing description or shown in the accompanying drawings shall be interpreted as illustrative and not in a limiting sense.

What is claimed is:

In a fuse-holding switch, in combination, a base, an angle member mounted thereon, a fuse-holding contact having laterally extending jaws, side walls and a flat attaching portion, the said attaching portion abutting 40 an arm of the angle member, a bridging element comprising a metal extension fitted between the side walls of said fuse-holding contact, means comprising a pivot screw for associating the angle member, carrier extension and fuse-holding contact together in electrical communication and providing for the movement of said carrier pivotally relatively to said base, co-operating contacts, one on said base and one on said bridging element near the free end thereof, and a second fuse-holding contact carried by said bridging element in electrical communication with the last said contact.

BRYSON D. HORTON.
